PICKER CHECK ASSEMBLY FOR LOOMS
Adelard J. Arcand, Biddeford, Maine, assignor to Pepperell Manufacturing Company, Boston, Mass., a corporation of Massachusetts

Filed Aug. 17, 1960, Ser. No. 50,178
11 Claims. (Cl. 139—165)

This invention pertains to textile apparatus, particularly to an improved picker check assembly for weaving looms. More specifically, the invention relates to that type of picker check wherein an elongate guide rod, fixed to a bracket depending from the loom lay, passes through holes in a looped leather strap, which receives the blow of the picker stick and which, in response to said blow, frictionally resists motion along said rod.

In checks of this general type, the strap loop also passes between elements of a friction device fixed to the lay of the loom, at the opposite side of the picker path from said rod, so that motion of the strap is frictionally opposed at both sides of the picker path. When the strap is struck by the picker stick the strap loop elongates and slides between the elements of the friction device, at one side of the picker path, and along the rod at the other side of the picker path. At the extreme limit of its motion the strap of the customary prior check may encounter the bracket which supports the rod, and repeated contacts with this bracket tend rapidly to wear and weaken the strap. It has been proposed to reinforce the strap against such wear by thickening the strap at those portions at which it may contact the bracket, as by making the strap of two or more thicknesses throughout, or by adding one or more lengths of strap material to the strap proper at its opposite end portions. However, since the picker stick oscillates about a fulcrum point below the location of the strap, the picker stick, when at its limits of motion, inclines outwardly, away from the vertical plane of its fulcrum, and in order that the picker stick may contact the check strap throughout the entire vertical width of the latter (thereby to avoid concentration of the blow upon a narrow limited area or edge of the strap) it is desirable that the strap be quite flexible so that when struck by the picker stick it may readily take the form of a frustum of a hollow cone so as to present a substantial portion of its width for contact by the stick. Thickening the strap at its end portions, as by the addition of extra layers, has the effect of stiffening the strap and thus reducing its ability to deform in response to the blow of the picker stick.

The present invention has for an object the provision of a novel picker check assembly wherein those portions of the strap which are encountered by the picker stick are of a single thickness so as to be of maximum flexibility and thus capable of conforming to the picker stick at the time when contacted by the latter, but wherein adequate provision is made for protecting the strap from direct encounter with the bracket which supports the rod, thus greatly prolonging the life of the strap without sacrificing the desired flexibility. A further object is to provide a picker check assembly having provision at opposite sides of the picker stick path for frictionally retarding motion of the strap in response to the picker stick blow and wherein one of the friction means for retarding motion of the strap is a rod fixed relatively to the loom lay and which passes through aligned openings in the strap, and wherein the rod is rectilinear and devoid of any stop elements at its opposite ends, thus facilitating the application of a new strap when it becomes necessary to replace the strap, but with provisions for positively limiting motion of the strap along the rod while in use. A further object is to provide a picker check assembly of the above type wherein there is associated with the

2

bracket which supports the rod, a cushioning element which serves to limit motion of the strap longitudinally of the rod and which, at the same time, resiliently opposes motion of the strap and prevents direct contact of the strap proper with said bracket. A further object is to provide a picker check assembly of the above type wherein there is provided a cushioning element, associated with the bracket supporting the rod, and which comprises a second length of strap material bent to an arc and with openings at opposite sides of the bracket through which the rod passes, and which presents a smoothly arcuate outer surface for contact with the strap proper. Other and further objects and advantages of the invention will be pointed out in the following more detailed description and by reference to the accompanying drawings wherein:

FIG. 1 is a bottom plan view of the improved picker check assembly showing the lower surfaces of the brackets, at opposite sides of the picker stick path, which support the frictional retarding devices of the assembly, the picker stick being indicated in broken lines, the assembly being shown in inverted position to avoid obscuration of the strap and cushioning device by the brackets;

FIG. 2 is a perspective view showing the same parts as FIG. 1, also in inverted position, and looking from the side of the strap at which the ends of the strap are united;

FIG. 3 is a vertical section at the line 3—3 of FIG. 1; and

FIG. 4 is a fragmentary elevation, omitting the check strap, proper, and showing only the cushioning element and the friction rod through which the check strap passes.

Referring to the drawings, the numeral 10 designates a bracket (shown inverted) which, in use, is secured to the lay of the loom by means comprising a bolt 11 and which has a fixed friction finger 12 which engages the inner side of the check strap S, while an adjustable finger 13, also carried by the bracket 10, engages the outer surface of the check strap. The bracket 10 is located at one side of the path of the picker stick, the latter being indicated in broken lines at P, while a second bracket 14, also carried by the loom lay, is arranged at the opposite side of the picker stick path, this latter bracket being attached to the lay by bolts 15 and 16. This bracket comprises the member 17, constituting one element of a clamp whose complementary member 18 is connected to the part 17 by a bolt and nut 19, the parts 17 and 18 being operative to hold, in clamped relation between them, the horizontal rigid rod 20. This rod, as here illustrated, is a simple piece of round steel rod, rectilinear and devoid of any screw threads or enlargements of any kind at or near its opposite ends, so that it may readily be threaded through openings, but little larger than the rod, in the strap S. It is thus possible, as hereafter more fully described, without removing the rod from the supporting bracket, to thread its opposite ends through holes in the check strap S and without necessitating the provision of holes in the strap of a size too large to defeat the purpose of the rod.

In accordance with the present invention, a cushioning element C is so arranged as partially to embrace the clamp comprising members 17 and 18, this cushioning element preferably being of a length of leather strap similar to the strap S of a width, for example, of the order of two inches and having holes near its opposite ends through which the opposite end portions, respectively, of the rod 20 pass. The distance between these holes in the cushioning element C is such that when it is in operative position, as shown in FIGS. 1 and 2, it is bent to arcuate form, thus presenting a smoothly curved outer surface 21 toward the check strap S.

In assembling the parts, and before the rod 20 is mounted between the clamping elements 17 and 18, it is passed through the openings in the cushioning element

C. The clamping element 18 having first been retracted from the member 17, the midportion of the rod 20 is introduced between the members 17 and 18, the end portion S of part C having been drawn closely enough together so that its outwardly bowed portion may receive the member 17 between it and the rod 20. The rod 20 is now clamped in place by tightening the nut 19. The midportion of strap S is now interposed between friction elements 12 and 13 and the opposite end portions of the strap S are threaded onto the opposite ends, respectively, of the rod 20 and then the ends of the strap S are directly united by a clip E.

With this arrangement that portion of the strap which is contacted by the picker stick need be of but a single thickness and thus of maximum flexibility and when the strap is contacted by the picker stick and thus moved in one direction or the other, it is protected by the cushioning element C from direct contact with any part of the bracket 14. Since the strap material customarily employed (tanned leather) is somewhat resilient, part C tends to spring in yielding to the pressure of the check strap S, thus performing its protective function in the most effective manner.

It may be noted that the strap S is of such a length that when in the normal position, as shown in FIG. 1, the clip E, which unites the ends of the strap, is spaced substantially from the protecting and cushioning member C, so that the strap S is permitted to move in one direction or the other in frictional engagement with the rod 20 in response to the blow imparted by the picker stick, but that because of the cushioning element C, which is incapable of motion along the rod 20, the strap S is positively prevented from moving sufficiently far in either direction to escape from the ends of the straight rod 20, so that stop elements at the ends of the rod are unnecessary, the cushioning element providing a sufficient stop. With this arrangement, when the picker strap S is eventually worn so that it requires replacement, it is merely necessary to disconnect its ends at the clip E, remove the old strap and apply a new strap without requiring that the rod 20 be removed for this purpose.

While one desirable embodiment of the invention has herein been illustrated and described by way of example, it is to be understood that any and all modifications, either in respect to dimensional relationships, materials employed, or the means whereby the assembly is suspended from the lay, are to be regarded as within the scope of the invention as defined in the appended claims.

I claim:

1. In a picker check assembly of the kind wherein a check strap, of single thickness at those portions of its length which are encountered by the picker stick and which is of a flexibility such as to conform to the slope of the picker stick when contacted by the latter, has frictional engagement with elements carried by lay-supported brackets located at opposite sides, respectively, of the picker stick path, one of said elements being a simple rectilinear length of rigid rod of uniform diameter from end-to-end, means normally fixedly connecting the center part of said rod to its supporting bracket, the central portion of the check strap engaging the friction elements carried by the other bracket, means directly connecting the free ends of the strap, the latter having holes of a diameter but slightly greater than that of the rod, spaced from its respective free ends and through which the rod passes and guard means fixed to the bracket which supports the rod and which is operative to prevent contact of the check strap with the latter bracket as the check strap is moved in response to the picker stick blow, the ends of said rod being freely movable through the openings in the strap in assembling the parts without necessitating the prior removal of any part of the assembly.

2. A picker check assembly according to claim 1, wherein the length of the check strap is such that, when it is assembled with the friction elements and its free ends are

united, the strap is incapable of moving sufficiently far in either direction to escape from the ends of the straight rod.

3. A picker check assembly according to claim 1, wherein the guard means comprises an auxiliary strap having openings through which the opposite ends of the rod pass, the distance between the openings in the auxiliary strap being such that when it is assembled with the rod and supporting bracket, the auxiliary strap is bent to arcuate shape and partially embraces the bracket which supports the rod.

4. A picker check assembly according to claim 1, wherein the guard means comprises a fixed part interposed between the rod supporting bracket and the check strap and which presents a smoothly curved, convex exterior surface to the inner surface of that part of the check strap which extends from one of its rod-receiving openings to the other.

5. A picker check assembly according to claim 1, wherein the guard means comprises a length of material substantially like that of the check strap, interposed between that portion of the check strap which extends from one of said rod-receiving openings to the other and the rod-supporting bracket, the length of material which constitutes the guard means having holes spaced from its respective ends, through which the rod passes, and presenting a convex, arcuate, outer face to the inner surface of the check strap, the means whereby the free ends of the check strap are united being located at a point approximately opposite to the center of said convex surface of the guard means.

6. A picker check assembly according to claim 1, wherein the holes in the check strap, through which the rod passes, are of a size such that the check strap offers frictional resistance to movement in response to the picker stick blow, and wherein the guard means is so arranged and is of such material as resiliently to resist motion of the check strap toward the rod-supporting bracket as the loop formed by the check strap is elongated in response to the picker stick blow.

7. In a picker check assembly for looms comprising a check strap consisting of a single thickness of material at those portions of its length which are encountered by the picker stick and which is of a flexibility such as to conform to the slope of the picker stick when contacted by the latter, means directly uniting the free ends of the check strap thereby to form a closed loop, the check strap having holes spaced from its connected ends, respectively, through which a lay-supported friction member passes, said friction member being a single rectilinear length of rigid rod of uniform diameter from end-to-end and which passes through the holes in the check strap, means fixedly connecting the central portion of said rod to the lay with the holes in the check strap located at opposite sides, respectively, of said connecting means, the looped check strap being so arranged that the picker stick delivers blows alternatively against single thickness portions of the strap located at substantially equal distances from the means which unites the ends of the strap thereby causing the strap to slide in one direction or the other along said rod, and means located at the same side of the picker stick path as the means which unites the ends of the strap operative to prevent the strap from contacting the means which supports the rod, the strap being of such length that, when the parts are at rest, the means which unites the ends of the strap is spaced from said guard means, and the length of the strap being such that at maximum elongation of the looped strap, in response to the picker stick blow, the strap cannot escape from the rod.

8. In a picker check assembly of the kind wherein a check strap, consisting of a single thickness of flexible leather at those portions, at least, which are encountered by the picker stick, has its opposite ends directly connected by uniting means to form a loop which encompasses the path of the picker stick and wherein, at one

side of the picker stick path, a simple rectilinear length of rigid rod, parallel to the picker stick path, of uniform diameter from end-to-end and centrally supported on a bracket carried by the loom lay, has its opposite end portions, respectively, passing through openings in the check strap spaced from and located at opposite sides, respectively, of said uniting means, in combination, means located wholly within said strap loom operative to prevent contact of the strap with the aforesaid bracket, the length of the strap being such as to prevent its escape from one end or the other of the rod, in response to motion of the strap by the blow of the picker stick.

9. The combination according to claim 8, wherein the means for preventing contact of the loop with the rod-supporting bracket comprises a part located within the strap loop and fixed relatively to said bracket and which presents a convex, arcuate, outer surface for contact with that part of the inner surface of the check strap which extends from one of said openings to the other.

10. In a picker check assembly of the kind wherein a check strap has its ends directly joined by connecting means to form a loop so arranged that the picker stick contacts the inner surface of the strap at opposite portions, respectively, as the picker stick oscillates and wherein in the motion of the strap, in response to the blows of the picker stick, is frictionally resisted by means located at opposite sides, respectively, of the picker stick path, the means at one side of said path comprising a single length of rectilinear rod of uniform diameter from end-to-end, the midportion of the rod being fixed to a bracket carried by the loom lay, the strap having holes spaced, respectively, from said connecting means through which those portions, respectively, of the rod which are located at opposite sides of the supporting bracket pass at an angle such as frictionally to resist motion of the strap along the rod, in combination, an auxiliary strap of the same material as the check strap and which is fixed relatively to the bracket which supports the rod, said strap being of arcuate curvature with its concavity directed toward the picker stick path and so as partially to embrace

10 40
15
20
25
30

the bracket which supports the rod, said auxiliary strap presenting a convex surface toward the means which connects the ends of the check strap and thereby guarding the connected ends of the strap from direct contact with the bracket which supports the rod.

11. In combination with a loom having a picker stick which oscillates in a vertical plane about a fixed axis adjacent to its lower end, a check strap having its ends united, one to the other, by connecting means to form a loop which embraces the free end portion of the picker stick and which is operative to limit motion of said end of the picker stick in either direction, said strap being of uniform width and of a material so thin and flexible that, when struck by the picker stick, that portion of the strap which receives the blow takes the form of a frustum of a hollow cone so as to provide a substantial portion of its width for contact with the stick, said strap having openings therein spaced equally from its united ends, both of said openings being located at the same side of the path of motion of the picker stick, a friction member consisting of a simple length of rectilinear rigid rod of uniform diameter from end-to-end which passes through both openings in the strap, a bracket fixed to the lay of the loom to which the midportion of said rod is secured in such a way that the rod is horizontal and parallel to the plane of motion of the picker stick, and resilient means located wholly within the loop formed by the strap operative to prevent contact of the strap with said bracket, the strap being of such length that it cannot escape from either end of the rod in response to elongation of the strap loom by the blow of the picker stick.
